UNITED STATES PATENT OFFICE.

FRANK R. McBERTY, OF NEW ROCHELLE, NEW YORK, ASSIGNOR TO WESTERN ELECTRIC COMPANY, OF CHICAGO, ILLINOIS, A CORPORATION OF ILLINOIS.

ELECTRIC CABLE.

1,054,784.

Specification of Letters Patent.

Patented Mar. 4, 1913.

Application filed February 27, 1908. Serial No. 418,121.

To all whom it may concern:

Be it known that I, FRANK R. McBERTY, a citizen of the United States, residing in the town of New Rochelle, in the county of 5 Westchester and State of New York, have invented a certain new and useful Improvement in Electric Cables, of which the following is a full, clear, concise, and exact description.

10 My invention relates to an improved form of cable of the general type of that illustrated and described in my application Serial No. 418,122, filed February 27th, 1908, and adapted for the same sort of use as is 15 set forth in the said companion application.

The invention of the present application is particularly directed toward the provision of a cable of simple construction which may be manufactured at a small cost, which may 20 be formed for connection with the terminals which it is adapted to unite without individual manipulation of its wires, and which will have the minimum of bulk for a given wire capacity, in order that the terminals 25 may be connected without being obstructed in any way by the connecting cable.

In the improved form of cable to which my present invention relates, these results are secured by interweaving the electrical 30 conductors and the insulating material of which the cable is composed, so that the conductors are held together and at the same time insulated from each other and from surrounding objects by means of interwoven 35 insulating material.

In the form in which I prefer to practice my invention the wires or conductors form the warp of the woven cable, while the woof is formed of insulating material. The cable 40 is preferably woven in the form of a flat band or ribbon having the conductors arranged in a layer extending longitudinally of the ribbon, while the insulating thread is interwoven with the conductors transversely 45 of the ribbon. In the process of weaving this flat or ribbon cable, the insulating woof is discontinued or separated at intervals along the cable so that spaces are formed where the wires are bare and exposed for 50 connection with the terminals which they are adapted to unite. In forming the cable for connection with the associated terminals, it may be folded upon itself along these lines of discontinued insulation in order to form 55 terminal projections on the bare portions of the wires. The thinness of this ribbon cable

of my invention—the cable being only as thick as the diameter of a single one of its wires plus the thickness of two insulating threads—particularly adapts it for use in 60 association with closely spaced rows of terminals, such, for instance, as are employed in automatic switches for connecting telephone lines, as it is possible to locate the cable in the slight space separating adjacent 65 rows so that it is entirely within the plane of the outer ends of the terminals, or in other words, to the rear of said outer ends of the terminals.

I will describe my invention more particularly by reference to the accompanying drawings, in which—

Figure 1 shows a length of cable embodying my invention; Fig. 2, an enlarged cross section of the cable on line 2—2 of Fig. 3; 75 Fig. 3, the cable shown in Fig. 1 with the sections of the cable on opposite sides of the lines of discontinued insulation opened out; Fig. 4, the cable folded upon itself along the exposed lines and at intermediate points to 80 adapt it for connection with rows of terminals; Fig. 5, a side view of two groups of terminals connected together by woven cables in accordance with my invention; and Fig. 6, a top or plan view of the connected groups 85 of terminals illustrated in Fig. 5.

In describing my invention by reference to the drawings, I shall employ the same reference characters to designate the same parts in the different figures. 90

The cable *a* of my invention in the form in which I prefer to employ it, consists of a ribbon of wires or conductors *b* held together and at the same time insulated from each other and from external objects by 95 means of insulating thread *c* woven about the conductors. The ribbon cable may be woven in a loom, the wires *b* forming the warp of the woven fabric and the insulating thread *c* the woof of the fabric. The wires 100 *b* may be of any suitable conducting material and dimensions. I have found it convenient in some cases to employ No. 28 gage tinned copper wires for the conductors of the cable. The insulating woof may also be 105 of any suitable material and dimensions. I have found that No. 40 mercerized cotton thread is suitable for this purpose, and it is obvious that wool, silk or other insulating fiber may be employed.

In weaving the cable I omit the insulating covering from the wires at intervals along 110

their length in order that they may be exposed and made accessible for connection with the terminals to which they are adapted to be joined. These exposed spaces are illustrated at *d* in the drawings, and are preferably distributed along a line oblique to the length of the cable in order that the bared portions of the wires may correspond in position with the position of the terminals with which the cable is to be connected. The angle which the line of omitted insulation forms with the long dimension of the cable depends upon the relation of the width of the cable to the length of the row of terminals to which it is to be connected. If the length of the row is equal to the width of the cable, the line of discontinued insulation will extend straight across the cable at right angles to its length. As the ratio of the length of the row to the width of the cable increases, the angle formed by the exposed line with relation to the length of the cable becomes more acute,—the length of the line of omitted insulation being, of course, substantially equal to the length of the row of terminals.

The wires may be exposed for connection at the points *d* in any convenient manner; but the manner in which I prefer to accomplish this is by omitting or discontinuing the insulation from the wires at these points in the process of weaving the cable. This may be done, where the line of omitted insulation extends diagonally across the cable, by employing a two shuttle Jacquard loom, and operating this loom so as to cause the shuttle on one side to carry the threads across an intermittently increasing number of the wires which constitute the warp of the fabric, and at the same time causing the other shuttle to carry its threads across a correspondingly decreasing number of the wires of the ribbon. One wire between the shuttles is left free from the insulating thread, and in the progressive alteration of the scope of the movement of the shuttles the insulating covering is omitted from each of the wires of the cable in turn. If desired, the loom may be operated so that all the wires of the ribbon are at all times included in the woof woven by one or the other of the shuttles. In this case no bare portions are left in the fabric as it comes from the loom, but the wires are bared thereafter—in the process of forming the cable for connection—by pushing back the woof on both sides of the dividing line between the portion woven by one shuttle and that woven by the other, thus separating the two portions and leaving an exposed line between. Or, if desired, the fabric may be so woven that portions are left bare, on one wire after another, while between the bare portions both shuttles carry their threads across the entire width of the ribbon, thus binding the two portions of the

woof together, and preventing the bare portions from being closed up by the spreading of the threads. The method of weaving the cable of my invention and of baring the wires at intervals to expose them for connection, however, I am reserving for another application. 70

In forming the woven cable of my invention for connection with the terminals that it is adapted to unite, I am enabled to bring out bare portions of the wires for being joined to the terminals without requiring an individual manipulation of the wires. The method of forming the cable which I prefer to employ consists in displacing the two sections of the cable on opposite sides of the line of omitted insulation *d*, by pushing forward one of the sections relatively to the other and in the same plane, so as to bend the exposed portions of all the wires at an angle to their normal direction, and substantially at right angles to the line of the exposed portions. This operation not only opens out the cable for connection, but also forces back the insulating woof and holds it in place at the ends of the bare portions, as illustrated in Fig. 3 of the drawings. The next operation in the forming process, which consists in folding the cable upon itself along the exposed line *d*, changes the form of the cable 90 to that which is illustrated in Fig. 4 of the drawings. This treatment, as the drawings show, produces terminal projections on each of the wires of the cable, by means of which the cable wires may be joined to the apparatus which they are adapted to connect. 100

In Figs. 5 and 6 I have illustrated the manner in which the woven cable of my invention may be employed for connecting electrical terminals which are mounted in groups and in very close relation to each other. I have here illustrated two groups of terminals *e* and *f*, respectively, each group comprising six rows of terminals thirty to the row. Each cable is connected to corresponding rows of terminals in the two groups, and may be extended to corresponding rows of terminals in other groups not shown, each terminal to which a conductor of the cable is connected being adapted to have completed through it a branch circuit of that conductor. Each cable extends to one side of the row of terminals it is adapted to serve, is folded over the top of the row along the line of omitted insulation, and the exposed portions of the conductors soldered to the corresponding terminals, the cable leaving along the other side of the row of terminals. It is customary, in the type of automatic switches for connecting telephone lines with which, as hereinbefore stated, my improved cable is particularly adapted to be used, for the terminals to project through their insulating support. At the left in Fig. 5 I have shown only two of the termi- 125 130

nals of the group *e* as so projecting through their insulating support. To illustrate the manner in which such terminals become part of a branch circuit, I have shown in diagram 5 a portion of an operator's cord circuit having at one extremity the movable brushes of the automatic switch and at the other extremity one side of the usual repeating coil, the other side of said coil (not shown) being connected with the answering plug. Intermediate with the groups of terminals, *e* and *f*, each of the cables has a fold *g*—or, if necessary, more than one fold—so as to bring the edge of the fold along the exposed 10 line *d* at the next group of terminals into line with the tops of the terminals in the row with which it is to be connected. Each of the rows of terminals in the two groups is connected in the same manner to one of the 15 flat cables that joins corresponding rows of the groups, the cable in each case lying between adjacent rows of terminals in the group and entirely within the plane of the outer extremities of the terminals, so that 20 the terminals are left unobstructed by the cables, and the cables are held in position and protected from injury. The extreme thinness of the woven cable of my invention renders it capable of being used in this manner to connect apparatus in which the 25 terminals are mounted very close together, and at the same time enables it to accomplish this without interfering with the accessibility of the connection between the cable 30 and terminal after the wiring is completed.

I claim—

1. A multi-conductor cable consisting of a woven ribbon of wires and insulating threads, with the wires forming the warp 40 and the threads the woof of the ribbon inclosing and insulating the wires, the woof being separated at intervals along each wire to expose the same for connection.
2. A multi-conductor cable consisting of a woven ribbon of wires and insulating thread in which the wires form the warp and the thread the woof of the ribbon inclosing and insulating the wires, the insulating woof being discontinued for short spaces at intervals along the ribbon to expose the wires for connection.

3. A woven cable in the form of a ribbon in which a plurality of conductors constitute the warp and insulating material the woof 55 of the ribbon, said insulating woof being discontinued at intervals along the ribbon on lines oblique to the length of the ribbon to expose the conductors for connection.

4. A woven multi-conductor cable in the 60 form of a flat ribbon in which the conductors form the warp and insulating thread the woof of the ribbon, said insulating woof being omitted at intervals along the ribbon on

lines oblique to the length of the ribbon, and the ribbon being folded upon itself on the lines of omitted insulation to form terminal projections on the exposed portions of the wires.

5. A flat woven multi-conductor cable having the insulation omitted from its wires 70 for short spaces at intervals along the cable to expose the wires for connection, the cable being folded upon itself along the lines of omitted insulation.

6. A woven multi-conductor cable in the 75 form of a ribbon in which the conductors form the warp and insulating thread the woof of the ribbon, said insulating woof being omitted at intervals along the ribbon on lines oblique to the length of the ribbon, the 80 portions of the ribbon on opposite sides of said lines being displaced with relation to each other to bend the exposed portions of the wires at an angle to their normal direction, and the ribbon being folded upon itself 85 on the lines of omitted insulation to form terminal projections on the exposed portions of the wires.

7. In a multiple cabling system, the combination with groups of terminals arranged 90 in closely spaced rows, of flat woven cables connecting corresponding rows in each group, said cables lying between the rows of terminals and being folded over the associated row in each group to bring the wires 95 of the cable into position to be connected with the corresponding terminals.

8. A multi-conductor cable consisting of a woven ribbon of wires and insulating threads, the wires lying parallel in the same 100 plane and spaced slightly apart from one another, and the threads forming the woof of the ribbon and lying closely adjacent to one another and arranged to completely cover the wires except at intervals along each 105 wire, the orderly arrangement of the weave being altered at such intervals to expose the wires for connection.

9. The combination with a branch circuit of a woven multi-conductor having an insulating woof and a warp formed of individual conductors, said conductors having exposed portions at intervals for connecting the branch circuit with the multi-conductor.

10. A multi-conductor cable consisting of 115 a woven ribbon of wires and insulating threads, with the wires forming the warp and the threads the woof of the ribbon, the warp conductors being separated at intervals along their length from the woof to 120 expose the warp conductors for connection.
